UNITED STATES PATENT OFFICE.

CHARLES W. CARTER, OF DETROIT, MICHIGAN.

SANITARY COVER FOR WAGONS.

1,065,588.

Specification of Letters Patent. Patented June 24, 1913.

Application filed October 10, 1912. Serial No. 724,909.

To all whom it may concern:

Be it known that I, CHARLES W. CARTER, a citizen of the United States of America, residing at Detroit, in the county of Wayne and State of Michigan, have invented certain new and useful Improvements in Sanitary Covers for Wagons, of which the following is a specification, reference being had therein to the accompanying drawings.

This invention relates to a sanitary top for delivery wagons and the like which is adapted to prevent the ingress of dust or dirt or the like, that is rain proof, and that is so disposed that the contents of the wagon body is at all times accessible, there being no supporting member between the ends of the top when the latter is fully opened on one side.

The invention consists in the matters hereinafter set forth and pointed out in the claims.

In the drawings, Figure 1 is a view in perspective of a wagon box equipped with a top that embodies features of the invention; Fig. 2 is a view in transverse section of the box and top; Fig. 3 is an end elevation thereof; and Fig. 4 is a view in section and in detail of a joint between two sections.

Referring to the drawings, a wagon box 1 preferably with driver's set 2, has a front board 3 back of the seat and an end board 4, all of conventional construction. A pair of segmental or semi-circular end plates 5 are provided with dowel pins 6 adapted to enter sockets in the front and end boards of the box. A hasp 7 or other convenient means is used for securing each segment in place. The end plates are connected by a longitudinally disposed top member 8 which, if preferred, may be stiffened by an upright plate 9, the latter affording a convenient place for application of advertising matter.

Each end plate 5 has a bearing pin 10 at its center of curvature on which segmental frames 11 and 12 are swiveled, the frames each carrying curved cover boards 13 and 14 respectively. The frames and cover boards are so disposed that when turned into closed position their inner marginal portions overlap beneath the member 8, and each when turned uncover one side of the box and when turned down rest on the upper edge of the side 15 of the box. At their outer margins the cover boards 13 and 14 underlie a flange strip 16 secured on the end plates 5, which insures a tight joint. In

order to allow access to one portion of the box without uncovering the other portion the cover boards are divided transversely or made in sections, these on the end frames, 11 having a rabbet joint or tongue-and-groove construction indicated in Fig. 4, in which the marginal portion 17 of one board lies between end flanges 18 of the companion board. Similar arrangement is made for the meeting edges of the two sections carried by the frames 12. As a convenient form of construction and for the sake of symmetry and appearance the outer one of the members 18 is continued around the side 70 and other end margins of the member 14 to give it a panel effect while a similar effect is obtained by facing strips 20. Handles 19 or other convenient means are provided for raising and lowering the sections. As a result of this construction a sanitary cover is provided which may be bodily removed from a wagon box and which when applied thereto, affords protection from dust and water and gives easy access to articles in 80 any portion of the box without uncovering the whole of the box. Either side of the box may be uncovered throughout the entire length, and as there is no middle support, articles as long as the box will contain may be readily loaded on or removed from the vehicle to which the top is applied.

Obviously, changes in the details of construction may be made without departing from the spirit of my invention and I do not care to limit myself to any particular form or arrangement of parts.

What I claim is:

1. The combination with a wagon box having front and end boards of a top therefor consisting of a pair of segmental end plates adapted to rest on the front and end boards of the box, means detachably securing the plates in position, a top member connecting the upper portion of the end plates, 100 and a pair of curved cover boards pivotally secured to the end plates to swing past each other, the upper margins of the cover boards overlapping and the lower margins contacting with the box side when the top is closed, each cover board being transversely divided between its ends to form sections and the adjacent margins of such sections having interlocking sliding engagement with each other whereby any one section may be raised 110 without disturbing the other sections.

2. A wagon having a front board and an

2

end board and a top therefor consisting of a pair of segmental end plates, guides for holding the end plates in alinement on the front and end boards respectively, means detachably securing the end plates in position, a longitudinally disposed top member connecting the upper portions of the end plates, a bearing member on each end plate in substantially axial coincidence with the center 10 of curvature thereof, a pair of quadrant frames journaled on each bearing member to swing past each other from side to side of the box, and sections of cover boards carried at the outer ends by the oppositely disposed members of each pair of quadrant frames, and interlocked in sliding engagement at the inner, meeting margins, the sections when in closed position spanning the wagon box between the sides and end plates.

15 3. The combination of a wagon box having front and end boards therein, of a top consisting of a pair of end plates resting respectively on the front and end boards, means detachably securing the plates in po-

sition, a top member secured to the upper 25 portions of the end plates, an inwardly projecting flange on the curved margin of each end plate, quadrant frames each pivoted at substantially the center of curvature of an end plate, a pair of curved cover boards divided transversely into sections, the outer 30 end portions of which underlie the end plate flanges and are supported by the quadrant frames, and the inner end portions of which are in interlocked sliding engagement, the 35 cover boards being adapted to inclose the box between the sides and end plates when the outer lateral margins of the several sections are in contact with the box sides, and each section of the top being movable independently of the other sections.

In testimony whereof I affix my signature in presence of two witnesses.

CHARLES W. CARTER.
